A. Jacobs,

Washing Machine,

No 16,567

Patented Feb. 3, 1857

UNITED STATES PATENT OFFICE.

AMOS JACOBS, OF ITHACA, NEW YORK.

WASHING-MACHINE.

Specification of Letters Patent No. 16,567, dated February 3, 1857.

To all whom it may concern:

Be it known that I, AMOS JACOBS, of the town of Ithaca, in the county of Tompkins and State of New York, have invented a new and Improved Washing-Machine; and I do hereby declare that the following is a full and exact description thereof, reference being had to the accompanying drawings, and to letters of reference marked thereon, 10 and in which—

Figure I, is a general sectional view of my machine; Fig. II, a vertical or perpendicular view of my tub, and tubs. Fig. III, is a side view of my machine.

15 The nature of my invention consists in so arranging the tub and dasher, that the former shall be rotated by the latter, as herein described.

To enable other skilled in washing by machinery to make and use my invention, I 20 will proceed and describe its construction and operation.

In Fig. 1, X, X, with the sides toward B, B and B, B, is an outward tub, or other support. In it the tub Y, Y, is suspended by means of the shaft, T, on which said tub revolves, supported by the points W, W. Z, is a cover to one, or both of said tubs, made thick and stout to support, as in the drawing, 25 an oscillatory engine, though any other mechanical means may be used to move the dasher and tub Y, Y. The oscillating engine is supported by the columns M, and Q, by means of the points or journals R, and R. Similar supports or contrivances 30 may support a crank or other means when no engine is used. The dotted lines show the various positions which the piston, and the dasher V, occupies. H, the piston rod 35 that connects with the dasher or beater. The dasher is made thus: V, is a wood plate, or dasher or beater, so shaped as to strike at any angle; and with or without holes or other contrivances of the ordinary 40 hand dasher. U, U, is a spring that is fastened by its ends to the piston rod, though

whether said spring be used or not is not considered as essential.

Fig. II, is a perpendicular view of the tub. It represents it in its surrounding tub, 50 and as having its bottom perforated by holes, to allow the escape of sediment, and water. Fig. III, is designed to show the obliquity of the acting force, and its object, which is to cause the dasher so to impinge 55 or strike the clothes or other articles, as not only to wash them, but also cause the inner tub to revolve on its axis T, Fig. I.

It will be seen that a portion of the tub is represented as cut away further to show the 60 obliquity of the stroke and its object. The manner of using the machine is as follows: Into the inner and outer tubs I put water so as to fill them to the red dotted line x, a, Fig. I, or to any other desirable depth. 65 Next opening the stop cock N, I admit steam to the bottom of the outer tub, and sufficiently heat the water. When the water is heated, or while heating I put the clothes or other articles, with or without soap and 70 other materials, into the inner tub, and spread them over the perforated bottom of the inner tub. And when ready I move by hand the engine off of the "dead point," or otherwise start the engine. The engine by 75 acting so strikes, by means of the dasher, the clothes or articles, that they are washed; and the inner tub is made to revolve.

What I claim as my invention, and desire 80 to secure by Letters Patent is—

The combination of an oblique beater or dasher, with a tub, constructed substantially as described; in such a manner that the stroke of the dasher or beater causes the tub or vessel to revolve; for the purposes of 85 washing, cleaning, stamping and rinsing clothes.

AMOS JACOBS.
